UNITED STATES PATENT OFFICE.

OSCAR B. WELKER, OF MIDDLETOWN, CONNECTICUT, ASSIGNOR TO THE WELKER-HOOPS MANUFACTURING COMPANY, OF MIDDLETOWN, CONNECTICUT, A CORPORATION OF CONNECTICUT.

CLOSURE FOR TANKS.

Application filed October 25, 1924. Serial No. 745,733.

To all whom it may concern:

Be it known that I, OSCAR B. WELKER, a citizen of the United States, and a resident of Middletown, in the county of Middlesex and State of Connecticut, have invented new and Improved Closures for Tanks, of which the following is a specification.

My invention relates to means for closing the filling opening of a tank or other similar structure, and an object of the invention, among others, is to provide a closure for such opening, which closure shall be permanently attached to the tank in a manner to permit ready and unobstructed access to such opening for the purpose of filling the tank, or for such other purpose as may be desired.

One form of a closure embodying my invention and in the construction and use of which the objects herein set out, as well as others, may be attained, is illustrated in the accompanying drawings, in which—

Figure 1 is a top view of my improved closure.

Figure 2 is a view in elevation of the same.

Figure 3 is a view in elevation as seen from a point located at right angles to the point of view of Figure 2.

Figure 4 is a view in section on a plane denoted by the dotted line 4—4 of Figure 1.

Figure 5 is a view in section on a plane denoted by the dotted line 5—5 of Figure 2, the open position of the cap being shown in dotted outlines.

Figure 6 is a perspective view of my improved closure with the arms broken off.

In the accompanying drawings the numeral 7 indicates the base of my improved structure that is adapted to be affixed to the opening of a tank or other similar receptacle, as by means of a threaded neck 8 fitting a screw threaded opening in the tank in a manner that will be readily understood.

45 A shoulder or seat 9 is formed within the base 7 and locking slots 10 are formed in the wall of the mouth 11 of the base, receiving openings 12 extending from the edge of the base into the slots 10.

50 A support 13 is hinged to one side of the base 7, this support preferably having a dome 14

with an opening through which the end of a hub 15 from a cap 16 extends, any suitable means, as a nut 17, being employed to secure the hub 15 to the support 13.

55 The cap 16 is provided with fastening lugs 18 located preferably on diametrically opposite sides of the cap and of a width to be received within the openings 12 and of a thickness to fit the slots 10. The hub 15 is so secured to the support 13 that the cap may be freely turned on such support, and independently thereof, and arms 19 extend from the cap as a means for turning it.

60 A hole 20 may be formed through the hub 15 and may be closed by a member 21, these parts, however, not having any special significance with respect to the invention.

65 A gasket 22 may be placed upon the shoulder 9 to receive the support 13 and insure the sealing of the closure at this point. This gasket is preferably of resilient material so that the pressure against the cap 16 will cause sufficient friction to insure retention of the lugs 18 in the slots 10.

70 While this device is not limited in its use to a receptacle of any special construction it has been found to be extremely advantageous as a closure for the filling mouth of a radiator for automobiles.

75 In order to secure the device against petty meddling or pilfering a threaded hole 23 is formed in the wall of the opening and extending inwardly from the shoulder 9, this hole cutting through substantially the crowns of the threads on the neck 8. A screw 24 is inserted into this hole after the structure has been secured in place, the screw being forced in in a manner to mutilate the threads. The screw may be inserted sufficiently below the shoulder 9 to leave a space within the hole which may be filled with metal that may be tamped into place, if sufficiently soft, or that may be melted and run into the opening.

80 In accordance with the provisions of the patent statutes I have described the principles of operation of my invention, together with the device which I now consider to represent the best embodiment thereof; but I 85 desire to have it understood that the device shown is only illustrative and that the in- 90 95 100

vention may be carried out by other means and applied to uses other than those above set out.

I claim—

5. 1. A tank closure comprising a base, a support, means for movably, permanently attaching the support to the base, a cap swivelly and permanently attached to the support against lateral and longitudinal movement independently thereof, and means for temporarily locking the cap to the base.
10. 2. A tank closure comprising a base having an opening therethrough, a support, means for pivotally and permanently attaching the support to the base, a cap pivotally attached to the support against lateral and longitudinal movement independently thereof and closing the opening through said base, and means for temporarily locking the cap to the base.
15. 3. A tank closure comprising a base having an opening therethrough, a support, a hinge for attaching the support to the base, a cap swivelly attached to the support against lateral and longitudinal movement independently thereof and closing the opening through said base, and means for locking the cap in engagement with the base.
20. 4. A tank closure comprising a base having a locking slot with an opening thereto, a support, a hinge for attaching the support to the base, and a cap swivelly at-

tached to the support against lateral and longitudinal movement independently thereof and having a lug to pass through said opening and to engage said slot to lock the cap to the base.

5. A tank closure comprising a base having means for removably securing it to a tank and having a slot through the side wall thereof, a support having a lug pivotally attached to said base within said slot, and a cap having a hub swivelly attached to said support, said cap and base having at their meeting edges a lug on one part adapted to engage an angular slot in the other part.

6. A tank closure comprising a base and a cap, one of said members having a locking slot for engagement by a lug on the other member to secure the cap in locked position, a support to which said cap is swivelly attached against lateral and longitudinal movement independently of said support, and a hinge for attaching the support to the base.

7. A tank closure comprising a base having a locking slot, a support, a hinge for attaching the support to the base, and a cap swivelly attached to the support against lateral and longitudinal movement independently thereof and having a lug to pass into and engage said slot to lock the cap to the base.

OSCAR B. WELKER.
